UNITED STATES PATENT OFFICE

155,595

DESIGN FOR A BOTTLE

John H. Funkey, Baltimore, Md., assignor to Carr-Lowrey Glass Co., Baltimore, Md.

Application January 9, 1948, Serial No. 143,634

Term of patent 14 years

(Cl. D58—6)

To all whom it may concern:

Be it known that I, John H. Funkey, a citizen of the United States of America, residing at Baltimore in the State of Maryland, have invented a new, original, and ornamental Design for a Bottle, of which the following is a specification, reference being had to the accompanying drawing, forming part thereof.

Figure 1 is an elevation of the bottle as viewed from any side, showing my new design.

Fig. 2 is a top plan view.

I claim:

The ornamental design for a bottle, as shown.
JOHN H. FUNKEY.
